DRAW LEAF EXTENSION ATTACHMENT
FOR TABLESJack Weller, Lee, London, England, assignor to
Sankey-Sheldon Limited, Bilstion, England, a
company of Great BritainApplication February 21, 1950, Serial No. 145,323
In Great Britain February 25, 1949

5 Claims. (Cl. 311—55)

1

This invention relates to tables, desks and like articles, of that kind having a top part beneath which is disposed a draw-leaf or the like mounted on, or attached to, a slide for movement therewith from a position under the said top to an extended position beyond an edge of the latter, the said draw-leaf being pivotally or otherwise coupled to the slide, such as by links, so that it is capable, in its extended position, of a raising and lowering movement relatively to the slide, so that it may move into, or out of, a position level with the upper surface of the table, desk or like top being raised as soon as it is clear of the latter by a spring.

In the arrangements of the above kind, difficulty is experienced in so arranging the spring and the links or parts coupling the extension leaf to the slide to ensure that the leaf is raised automatically, as soon as it is clear of the top, into the desired position, so that it lies level or flush with the upper surface of the said top. An object of the present invention is to provide simple effective and positive means for causing elevation or raising movement of the leaf when it is drawn from beneath the top, to thereby bring said extended leaf to a position where its upper surface will be flush with the upper surface of the top, and one of its ends closely positioned adjacent to an end of the top. A further object is to provide adjusting means to ensure the proper registration of the draw-leaf with the top of the table, desk or the like.

According to the invention, a table, desk or like article, of the kind referred to, is provided with means for positively raising the draw-leaf, as soon as the latter has been moved clear of the top of the table, desk or the like. Preferably, the draw-leaf is positively raised up by cam means, the latter comprising an inclined part or ramp fixed relatively to the draw-leaf and engaged by a roller or other part thereon as the draw-leaf is moved clear of the top of the article, the positive upward movement bringing the links into positions in which they can be readily influenced by the spring. The roller or ramp engaging part may be attached to the draw-leaf by a pivoted, depending bracket which swings back to allow of the roller or ramp-engaging part wiping over the ramp as the draw-leaf is pushed back beneath the top of the article, the bracket being prevented from swinging in the opposite direction, beyond a predetermined position, by a stop. The leaf may be connected at each side by a pair of links to a slide-bar movable over a fixed guide, with a suitably disposed spring between the leaf

2

and slide bar for raising the leaf, and a pair of ramps may be provided one at each side, each adapted to be engaged by a roller on a depending pivoted bracket carried by the draw-leaf.

5 Figure 1 of the accompanying drawings represents a perspective view of a unit fitting for attachment to, and for forming part of, a table or desk structure, and comprising a top and a draw-leaf disposed beneath the latter, the draw-leaf being adapted to be positively raised up, when withdrawn, in accordance with the present invention.

Figure 2 shows the unit with the draw-leaf withdrawn.

15 Figure 3 represents a section through the unit upon a larger scale, with the draw-leaf in its pushed-in position.

Figure 4 is a cross-section on the line IV—IV, Figure 3.

20 Figure 5 is a sectional view showing the draw-leaf drawn out into a position for use.

Figure 6 represents a longitudinal section, upon a larger scale, through adjacent parts of the top portion and draw-leaf, just before the 25 latter has moved from beneath the top, showing one of the rollers just before it engages the ramp for positively lifting the draw-leaf.

Figure 7 shows an alternative construction.

Referring to Figures 1 to 6 of the drawings, the 30 improved device consists of a unit fitting comprising a top 1 disposed above, and fixed to, a box-like body part or casing 2, the latter being adapted to be secured to an undersupport forming part of a table or desk, so that the device forms a self-contained part of the latter. The 35 body part or casing 2 consists of a front member 3 of an inverted channel shape connected to sides 4, which are joined at their rear ends by a cross member 5, the box-part, thus formed, being divided by fixed vertical partitions 6, extending from front to back and providing side compartments 7 each closed at the bottom which is provided with tapped bushings 8a for receiving fixing screws or bolts, so that the device may be 40 attached to the desk or table frame. The device may be formed mainly from sheet metal, the top 1, which may be strengthened upon its underside by channels 8, being fixed to the understructure, such as by screws 9 passing through inturned flanges 10 of the latter. The front member 3 is 45 of less depth than the sides and back of the structure, so that there is left above the member 3 a slot, extending from side to side, for receiving a draw-leaf 11. The latter, which may be likewise 50 formed of sheet metal, has depending side

walls, with inturned lower edges, and with front and rear walls 13 and 14 respectively, likewise having inturned lower edges, whilst the said draw-leaf is strengthened upon its underside by channels 15 (Figure 4) extending from the front to the rear, one near each side above the partitions 6. The draw-leaf 11, thus constructed is slidably mounted beneath the top 1 upon a pair of channel-sectioned slides or runners 16, disposed one at each side, and extending from the front to the rear, the said slides or runners being set on edge with the channels presented towards one another, and each engaging a guide bar 17 fixed, such as by bolts 18, to the partition 6 at the respective side of the device. The draw-leaf 11 is connected to each runner 16 by a pair of parallel-motion links 19 and 20, pivotally connected to the runner 16 at their lower ends. The upper end of the one link 19 is pivoted to a bracket 12 on the underside of the draw-leaf, whilst the upper end of the other link 20 is pivoted to an extension arm 21 fixed to the underside of the draw-leaf and extending rearwardly therefrom, as shown. The two slides or runners 16 are joined together at their rear ends by a cross-bar 22, and at their forward ends by a cross-bar 23, thereby forming a rigid rectangular slidable frame. Owing to the arrangement of the channelled slides or runners 16 the oiled or greased surfaces of the latter are presented inwards and are not likely to come into contact with the clothes of the user.

Fixed upon the front cross-bar 23 connecting together the forward ends of the runners is a pair of upstanding brackets 24 forming anchorages for the rear ends of a pair of coiled extension springs 25, each spring being attached at its forward end to a bracket 38 on the underside of the draw-leaf 11. When the latter is not required for use it is housed wholly beneath the top 1, as shown in Figures 1 and 3 of the drawings, the links 19 and 20 assuming the positions indicated and the spring 25 being extended. When the leaf 11 is withdrawn from beneath the top it is caused, when released, to move upwards the links 19 and 20 moving angularly about their lower ends. To initiate this upward movement and to ensure that the draw-leaf 11 shall always move automatically into a position at which it is level with the table top means are provided for positively raising up the draw-leaf as it is withdrawn from beneath the top 1. For this purpose, there is formed out of the front member 3 of the casing 2 a pair of ramps 26 disposed one at each side of the structure and formed conveniently by cutting the top and side walls of the member 3 and bending down the cut-out part to the required shape, the lower ends of the ramps 26 being fixed, such as by spot-welding, to the bottoms of the compartments 7 at the two sides. Carried by the rear end of the extension arm 21 at each side of the draw-leaf 11 is a bracket 27 and pivoted between the side of the latter and the side of the arm 21 is a depending member 28 carrying a roller 29 and provided with a pivot 30. This roller-carrying member 28 is free to swing angularly forwards about the pivot 30 from its normal vertical position shown by full lines in the drawings, into, for example, the position indicated by dotted lines in Figure 6. The roller-carrying member 28 is positively prevented from moving angularly in a rearward direction, beyond its vertical position, by a suitable stop, such, for example, as by the stop 31, Figure 6.

As the draw-leaf 11 is slid out, with the run-

ners 16, from beneath the top 1, the rollers 29 carried by the depending members 28 engage against the ramps 26, and, riding up the latter, positively lift up the rear end of the draw-leaf 11 just as the same is leaving the top 1, so that it is caused to rise up nearly level with the said top. This lifting action causes, at the same time, angular movements of the links 19 and 20 from their lowered positions shown in Figure 1, and a positive upward movement of the whole draw-leaf is thereby effected. The springs 25 assist in this raising action, the initial lifting action of the ramps bringing the draw-leaf under the effective control of the said springs. Immediately the draw-leaf 11 is released the latter is moved back automatically so that its rear edge 14 is caused to abut closely against the forward edge of the top 1, as shown in the drawings. Not only do the ramps effect a positive raising of the draw-leaf, but by causing an initial angular movement of the links 19 and 20 the latter are prevented from sticking in their turned-down positions shown in Figure 3, as they might possibly do if the springs 25 alone were relied upon for the lifting action. The leaf 11 may be drawn out from beneath the top 1 by a finger grip pull on its forward edge.

The rear wall 14 of the draw-leaf may carry rubber or other pads or buffers, such as 32, and in order to limit the forward movement of the runners or slides 16 which carry the draw-leaf stops, formed by a pair of bolts 33, may be provided. These bolts 33 are carried horizontally by depending brackets 34 on the slide frame and the heads of the bolts are adapted to contact with rubber or other buffers 35 on the rear wall of the front member 3 of the casing 2 when the slides or runners 16 are fully withdrawn. The bolts 33, constituting the stops are adjustable and may be locked in their adjusted positions by nuts 36. When the draw-leaf 11 is in its raised position accurate register between the upper surfaces of the table top and draw-leaf may be brought about by rotational adjustment of the stops 35. The effect of such adjustment is then to vary the inclination of the links 19 and 20, and so vary, within small limits, the height of the upper surface of the leaf.

When the draw-leaf 11 is not required it may be moved forwards to cause the links 19 and 20 to assume the substantially horizontal positions shown in Figure 3, and the leaf, with the slides or runners 16, may then be pushed back beneath the top 1. During this rearward movement the rollers 29 wipe over the ramps 26, the parts 28 by which they are carried moving angularly about their pivots, and finally assuming by gravity the vertical positions illustrated. The rear cross-bar 22 of the slide frame may carry buffers 37 which engage the rear wall 5 of the casing when the draw-leaf is pushed fully back beneath the top 1.

Not only is a positive lifting action of the draw-leaf obtained, by the present invention, but perfect register of the upper surfaces of the table or like top and the draw-leaf may be obtained when the latter is extended, whilst the leaf may be readily and quickly withdrawn by one hand, the raising of the draw-leaf being entirely automatic.

If desired, a positive lifting action of the draw-leaf may be obtained by reversing the arrangement, as indicated, for example, in Figure 7. Referring to this figure an inverted ramp or inclined part 38 is provided at each side of the draw-leaf 11 on the extension arm 21 carried by the respective side of the latter, the said inverted ramp or

inclined part 38 being adapted to co-operate with a roller 29 on an upstanding part 39 pivoted at 40 to the fixed part 3, the front vertical wall of which forms a stop, the part 39 being normally maintained against the said wall by a spring 41. As the draw-leaf 11 is being withdrawn, and just as it leaves the top 1, the inverted ramp or inclined part 38 strikes the roller 29 and is lifted up, thereby positively raising the draw-leaf 11. When the draw-leaf 11 is moved back beneath the top 1 the lower corner of the part 38 strikes the roller 29 and moves the member 39 back against its spring 41, thereby wiping over the roller.

I claim:

1. A table-top, a slide movable beneath the latter, a draw-leaf, parallel-motion links connecting the draw-leaf to the slide, so that it may be moved with the slide beneath the top or drawn out from beneath the same, a spring tending to lift the draw-leaf when withdrawn, a fixed ramp, a depending pivoted part carried by the draw-leaf, a stop for preventing angular movement of the pivoted part in a rearward direction, the said pivoted part, held against angular movement by the stop, engaging, and riding up the ramp as the draw-leaf is withdrawn so that the draw-leaf is positively raised as it passes from beneath the table top, the pivoted part moving angularly and wiping over the ramp when the draw-leaf is moved back beneath the top.

2. A table-top, a slide movable beneath the latter, a draw-leaf, parallel-motion links connecting the draw-leaf to the slide, so that it may be moved with the slide beneath the top or drawn out from beneath the same, a spring tending to lift the draw-leaf when withdrawn, a fixed ramp, a depending pivoted part carried by the draw-leaf, a roller on the pivoted part, a stop for preventing angular movement of the pivoted part in a rearward direction, the roller on said pivoted part, with the latter held against angular movement by the stop, engaging, and riding up the ramp as the draw-leaf is withdrawn so that the draw-leaf is positively raised as it passes from beneath the table top, the pivoted part moving angularly and the roller wiping over the ramp when the draw-leaf is moved back beneath the top.

3. A table-top, a slide movable beneath the latter, a draw-leaf, parallel-motion links connecting the draw-leaf to the slide, so that it may be moved, with the slide, to lie beneath the top or drawn out, with the slide, from beneath the top, a spring tending to lift the draw-leaf when the latter is withdrawn, means for positively raising the draw-leaf when it has been moved clear of the top, the spring serving to hold an edge of

the raised drawn-out draw-leaf against an edge of the top, means for varying the extent which the slide may be withdrawn in order to vary the inclination of the links when the edges of the draw-leaf and top are in engagement, in order to bring the upper surfaces of the top and draw-leaf into register.

4. A table-top, a slide movable beneath the latter, a draw-leaf, parallel-motion links connecting the draw-leaf to the slide, so that it may be moved, with the slide, to lie beneath the top or drawn out, with the slide, from beneath the top, a spring tending to lift the draw-leaf when the latter is withdrawn, cam means for positively

15 raising the draw-leaf when it has been moved clear of the top, the spring serving to hold an edge of the raised, drawn-out draw-leaf against an edge of the top, a screw device on the slide, a fixed part, the screw device engaging the fixed part when the slide is withdrawn and forming a stop, the screw device being adjustable, to vary the inclination of the links and the height of the drawn-out raised draw-leaf when the edge of the latter is engaging the edge of the top.

25 5. A table-top, a slide movable beneath the same, a draw-leaf, parallel-motion links connecting the draw-leaf to the slide so that the draw-leaf may be moved with the slide to a position beneath the top or drawn out from beneath the

30 same, a ramp, a pivoted part, a stop for preventing angular movement of the pivoted part in one direction, the said pivoted part, held against angular movement by the stop, engaging and moving over the ramp as the draw-leaf is withdrawn, so that the draw-leaf is positively raised as it passes from beneath the table top, the pivoted part moving angularly and wiping against the ramp when the draw-leaf is moved back beneath the top.
